UNITED STATES PATENT OFFICE.

JOHN HAMMANN, OF BELLEVILLE, ILLINOIS.

DESIGN FOR AN ANODE-PLATE.

SPECIFICATION forming part of Design No. 35,071, dated September 10, 1901.

Application filed February 2, 1901; Serial No. 45,788. Term of patent 14 years.

To all whom it may concern:

Be it known that I, JOHN HAMMANN, a citizen of the United States, residing at Belleville, in the county of St. Clair and State of Illinois, have invented and produced a certain new and useful Design for an Anode-Plate, of which the following is a full, clear, and exact description, reference being had to the accompanying drawing, forming part of this specification.

The figure in the drawing is a perspective view of an anode-plate, showing my new design.

As illustrated in the drawing, the leading or material feature of my design consists of a flat solid elongated body 1, having four rounded corners and at each end of which is

a pair of elongated projections 2, having rounded ends and perforations 3, said projections extending, respectively, from the body near each edge thereof and the rounded corners of the body merging into the outer edges of the projections and the end of the body of the anode-plate being flat and merging with curved lines into the inner sides of the projections.

What I claim as new, and desire to secure by Letters Patent, is—

The design for an anode-plate herein shown and described.

JOHN HAMMANN.

In presence of—

AUGUST SEMMELROTH,
JACOB LEINER.
